UNITED STATES PATENT OFFICE.

ORLAND F. BAUGHMAN AND JOSEPH HABART, OF LAKEWOOD, OHIO, ASSIGNEES TO THE BANKERS SAVINGS & CREDIT SYSTEM COMPANY, OF CLEVELAND, OHIO, A CORPORATION OF OHIO.

COIN BANK OR RECEPTACLE.

Application filed May 11, 1925. Serial No. 29,393.

This invention relates to a coin bank or receptacle and its objects are to provide a device of this character that is simple of construction, the same being made practically entirely of sheet metal stampings; that is particularly convenient of use, the closure locking in place when applied to the receptacle and moved or rotated slightly with respect thereto; that is practically immune from disorder and is very durable, there being no parts involved which are of a delicate nature or which are likely to wear to any appreciable extent; and that is economical of manufacture on account of the fact that most parts are die stamped from sheet metal, as above mentioned, thus insuring accuracy of size and shape and assurance of fit when the parts are assembled.

In the accompanying drawing, wherein the present preferred embodiment of the invention is illustrated, Fig. 1 is a plan view, and Fig. 2 is a side elevation, of our improved coin receptacle with the cover applied; Fig. 3 is a plan view of the receptacle with the cover removed; Fig. 4 is an inside view of the cover; Fig. 5 is a view, similar to Fig. 1, with a part of the face plate of the cover broken away to reveal the lock and interengaging parts of the cover and receptacle; and Fig. 6 is an enlarged fragmentary side elevation of the bank or receptacle with interlocking parts of the cover and receptacle shown in sectional detail.

The receptacle 1 may be of any desired shape, the same being shown in the present instance as of a shallow cylindrical form. An annular flange 2 extends inwardly from one edge of the cylindrical wall of the receptacle, and the same is provided with a plurality of radially disposed tongues 3 that are equally spaced apart about the circumference, and are in the same plane as, the flange 2, as best illustrated in Figs. 3 and 6.

The cover 5 is designed to fit over the open side of the receptacle and it has an annular depression 6 which fits within the opening defined by the flange 2. The central portion 7 of the cover is in substantially the same plane as the edge portion 8, the latter portion engaging the flange 2 when the cover is applied to the receptacle. Outwardly beyond the portion 8 there is a peripheral bead 9 that extends down over the adjacent edge

of the cylindrical wall of the receptacle. Between the annular depression 6 and the aforesaid edge portion 8 is a shoulder 10, and within the zone of this shoulder the cover is provided with a plurality of arcuate slots 12 which correspond in number and position with the tongues 3 of the receptacle. The corresponding ends of the several slots 12 are enlarged to provide openings 13 through which the tongues 3 may be projected when the cover is applied to the receptacle. After the cover is so applied, it may be turned with respect to the receptacle thereby to bring the tongues 3 within the restricted ends of the slots 12. The cover is thus held to the receptacle until it is rotated in the reverse direction far enough to again register the tongues 3 with the openings 13. This is ordinarily prevented by a lock which we shall now describe.

Disposed within an enlarged part 6a of the depression 6 is a spring 15 which has one of its ends secured, as by a rivet 16, to the cover 5, while the opposite end of the spring is formed to constitute a latch bolt 17 arranged to engage the tongue 3 which is projected through the slot 12 adjacent the bolt 17. A part of the spring 15 intermediate its ends is reduced considerably in width so as to make the spring more resilient at this point. The end of the bolt 17 is beveled or inclined on one side so that when the tongue 3 is extended through the opening 13 and is moved into the restricted end of the slot, the tongue will override the end of the bolt, the bolt snapping back of the tongue to prevent a reverse rotation of the cover.

A face plate 18 is applied to the cover and fits within the bead 9 thereof, and it is held to the cover by suitable means, as by the aforementioned rivet 16 which holds the spring 15 in place, and by a second rivet 19. The face plate 18 is provided with a key-hole 20 through which a suitable key may be inserted, the inner end of the key being guided within an aperture 21 that is formed within the depressed part 6a of the cover. The key is of such design that when it is turned it will engage the portion of the spring 15 adjacent the keyhole and retract the bolt 17 in a well known manner thereby releasing the tongue 3 and allowing the cover to be rotated with respect to the re-

ceptacle so as to bring all tongues into register with the openings 13 when the cover may be lifted from the receptacle.

5 A coin slot 25 is formed in the cylindrical wall of the receptacle.

Having thus described our invention, what we claim is:

1. A coin bank comprising a receptacle having a circular opening and a plurality 10 of tongues extending inwardly from the edge portion of said opening and equally spaced apart about the same, a cover having a depression fitting within said opening and provided with a plurality of arcuate slots 15 in the peripheral wall of the depression the corresponding ends of said slots being enlarged to provide openings through which said tongues are adapted to be projected, the tongues entering the restricted portions of 20 the slots when the cover is rotated in one direction with respect to the receptacle, and a spring bolt carried by the closure and housed within the depression thereof for engaging one of said tongues to hold the cover 25 against rotation in the reverse direction sufficiently to bring the tongues into register with the aforesaid openings, and means for retracting the spring bolt.

2. A coin bank comprising a receptacle 30 having a circular opening in one of its walls and a plurality of tongues extending radially inwardly from the edge of the opening and equally spaced apart about the circumference thereof, a cover having an annular depression arranged to fit within the opening of the receptacle, the cover having a plurality of arcuate slots in the zone between the annular depression and the portion of the cover outwardly beyond said depression, 35 the corresponding ends of the slots being enlarged to permit the tongues of the receptacle to pass into the slots when the cover is applied to the receptacle, the tongues entering the restricted portions of the slots 40 when the cover is rotated in one direction with respect to the receptacle, the annular depression of the cover having an enlarged part, a spring within said enlarged part of the depression, said spring incorporating a 45 latch bolt arranged adjacent one of the aforesaid slots and in a position to engage the tongue projected through said slot, a face plate applied to the cover and closing the open side of said depression, and means 50 for retracting the latch bolt.

3. A coin bank comprising a receptacle 55 having a cylindrical wall from one edge of which an annular flange extends inwardly to define a circular opening, tongues extending 60 inwardly from said flange and spaced equal distances apart about the same, a cover having a peripheral bead which is arranged to overhang the cylindrical wall of the receptacle and an annular depressed portion de-

signed to fit within the circular opening defined by the aforesaid flange, the cover having a plurality of arcuate slots which correspond in number and location with the tongues of the receptacle, the corresponding ends of the slots being enlarged to permit 65 the tongues to pass through said ends when the cover is applied to the receptacle, the tongues entering the restricted ends of the slots when the cover is rotated with respect to the receptacle, the aforesaid annular depression of the cover having an enlarged part, a spring within said enlarged part and having an end constituting a latch bolt that is adapted to engage one of the aforesaid 70 tongues when the same occupies the restricted end of the corresponding slot, a face plate applied to the cover for closing the open side of the depression and concealing the spring, and means for securing the face plate to the cover, the face plate having a keyhole 75 for the admission of a key by means of which the latch bolt may be retracted from holding engagement with the lug of the receptacle.

4. A coin bank comprising a receptacle 80 having a cylindrical wall from one edge of which an annular flange extends inwardly to define a circular opening, tongues extending inwardly from said flange and spaced equal 85 distances apart about the same, a cover having a peripheral bead which is arranged to overhang the cylindrical wall of the receptacle and an annular depressed portion 90 designed to fit within the circular opening defined by the aforesaid flange, the cover having a plurality of arcuate slots which correspond in number and location with the tongues of the receptacle, the corresponding ends of the slots being enlarged to permit 95 the tongues to pass through said ends when the cover is applied to the receptacle, the tongues entering the restricted ends of the slots when the cover is rotated with respect to the receptacle, the aforesaid annular depression of the cover having an enlarged 100 part, a spring within said enlarged part and having an end constituting a latch bolt that is adapted to engage one of the aforesaid tongues when the same occupies the restricted end of the corresponding slot, a 105 face plate applied to the cover for closing the open side of the depression and concealing the spring, and rivets for securing the face plate to the cover, one of the rivets serving also to secure the spring in place, the face plate having a keyhole for the admission of a key by means of which the latch bolt may be retracted from holding engagement with the lug of the receptacle.

In testimony whereof, we hereunto affix 115 our signatures.

ORLAND F. BAUGHMAN.
